UNITED STATES PATENT OFFICE.

ARTHUR A. BERNDT, OF CHICAGO, ILLINOIS, ASSIGNOR TO KURY BROS. CO., OF CHICAGO, ILLINOIS, A CORPORATION OF ILLINOIS.

CRATE.

Application filed June 6, 1924. Serial No. 713,188.

This invention relates to improvements in crates, more particularly crates of that character designed for the holding and transportation of bottles, and the invention has reference more particularly to improved means for reinforcing, bonding and protecting the corners of the crates, which, in practical usage, are frequently subjected to rough handling. The invention also includes improved stacking lugs which are commonly used in crates of this character to facilitate the piling up or stacking of several crates in a vertical column, and which, in the present invention, are preferably mounted on and fastened to the upper corner reinforcing and bonding devices.

Among the objects of the invention are, to provide a reinforcing device which will securely and strongly unite and bond together the side and end walls at the corners, to provide such a device which will protect the corner portions of the side and end walls in their upper and lower regions and also facilitate the nailing of the device without danger of splitting the wood; to provide a device of the character mentioned which will afford ventilation to the wood embraced thereby, permit it to readily dry out when wet, and thus avoid rotting of the wood; to provide a corner bond and protector which may be cheaply and economically manufactured in a die press from a single blank of sheet metal, and which, after application to the crate, may be folded and pressed tightly against the inner surfaces of the side and end walls, thereby locking the device against accidental separation, irrespective of the nailing; to provide a corner bond and protector adaptable alike to both the upper and lower corners of the crate, and also conveniently adapted for the application thereto of the stacking lugs; and to provide an improved stacking lug with means for attaching it to the upper edge of the crate and also strongly anchoring it in the inner surfaces of the walls adjacent to the corner, thereby providing a double fastening therefor.

Other objects and attendant advantages of the invention will be apparent to persons skilled in the art as the same becomes better understood by reference to the following detailed description, taken in connection with the accompanying drawing in which I have

illustrated a practical and preferred embodiment of the invention, and wherein— 55

Fig. 1 is a perspective elevation of a bottle crate equipped with my improved corner protectors and stacking devices;

Fig. 2 is a top plan view of one of the upper corners; 60

Fig. 3 is a vertical section on the line 3—3 of Fig. 2, illustrating the nailing of the corner reinforcement and stacker to the upper edges of the walls;

Fig. 4 is a vertical section on the line 4—4 of Fig. 2, more particularly illustrating the means for anchoring the stacker in the inner side of the wall; 65

Fig. 5 is a plan view, partly in horizontal section of one of the lower corners, on the line 5—5 of Fig. 1.

Fig. 6 is a vertical section on the line 6—6 of Fig. 5;

Fig. 7 is a vertical section on the line 7—7 of Fig. 5; 75

Fig. 8 is a perspective view of the sheet metal corner reinforcement in the form in which it is applied to the corner of the crate prior to securing it on the latter;

Fig. 9 is a perspective elevation of the stacker prior to nailing and anchoring it to the crate; 80

Figs. 10 and 11 are external and internal perspective elevations, respectively, of an upper corner portion of a crate equipped with my improved stacking lug only, omitting the corner reinforcement; 85

Fig. 12 is a top plan view of the construction shown in Figs. 10 and 11;

Fig. 13 is a vertical section on the line 13—13 of Fig. 12, more especially illustrating the manner of attaching the feet of the lugs by nailing; 90

Fig. 14 is a sectional detail on the line 14—14 of Fig. 12; and 95

Fig. 15 is a perspective elevation, generally similar to Fig. 9, of the form of stacking lug illustrated in Figs. 10 to 14 inclusive.

Referring to the drawings, 10 designates the side walls and 11 the end walls of a rectangular bottle crate which, so far as my present improvements are concerned, may be of any usual and well-known construction. Such crates are commonly provided with open work metal bottoms of various sorts to permit free drainage of 100 105

moisture from the surfaces of the bottles, and also with longitudinal and transverse spacing strips forming bottle cells. With these features of the crate, however, my present invention is not concerned.

The crate illustrated, however, is of that type which employs on its bottom a relatively low rectangular shoe frame or sole comprising side strips 12 and end strips 13 which, as shown in Fig. 7, are slightly thicker than the superposed side and end walls of the box body.

14 designates as an entirety the corner reinforcing, bonding and protecting member which, as best shown in Fig. 8, consists of a channel-shaped angle piece preferably bent to shape from a flat blank of sheet metal, and comprising a web portion consisting of vertical side walls 15 at right angles to each other and a rounded corner wall 16 connecting said side walls 15; and top and bottom horizontal flat flanges 17 and 18, respectively. In the case of the lower corners of the crate, one of these angle pieces is fitted onto the corner joint formed at the meeting of the side and end members 12 and 13 of the shoe frame, the upper, lower and outer surfaces of the latter being countersunk by the thickness of the metal, as shown in Figs. 5, 6, and 7, so as to bring the outer surfaces of the flanges 17 and 18 flush with the upper and lower surfaces of the frame member, and the outer surfaces of the web 15 flush with the outer surfaces of the crate walls 10 and 11. Holes 19 and 20 are formed in the flanges 17 and 18 respectively to receive nails 21 driven therethrough and into the lowermost body section of the crate.

By reference to Fig. 7 it will be noticed that the inner surfaces of the shoe frame members 12 and 13 are also countersunk, as shown at 22 by the thickness of the metal, making the frame members 12 and 13 at these points of equal thickness with the walls 10 and 11. After the corner piece has been thus applied, with the crate bottom side up, it is placed beneath a die which just fits the interior of the crate, and the descent of the die within the latter bends the projecting ends of the wings 17 and 18 flat against the inner walls of the shoe frame members 12, 13 and body members 10, 11, thereby forming lips 23 and 24, which clinch and securely anchor the metal corner piece to the interior of the crate, auxiliary to the holding effect of the nails 21. The lips 23 lie in the countersinks 22 of the shoe frame members, so that when pressed into engagement with the internal walls they lie in the same vertical planes with the lips 24. It will be observed that the lips 23 overlap only a portion of the inner sides of the frame members, so that the latter are not entirely surrounded by the metal, but are ventilated through the uncovered portions of their

walls, thus permitting them to dry out, if wet, and avoid rotting.

The corner reinforcement pieces at the four upper corners of the plate are structurally identical with the corner reinforcement pieces at the corresponding lower corners, and are applied in the same way by cutting kerfs 25 and 26 (Fig. 1) in the ends of the side and end walls 10 and 11 for the accommodation of the flanges 18 of the corner pieces, and also preferably countersinking the top edges of said walls, as shown at 25' and 26', for the accommodation of the flanges 17. When thus applied, the crate in upright form is subjected to a similar die-pressing action to bend and lay the lips 23 and 24 snugly over the inner sides of the walls 10 and 11.

To the four upright corners of the crate are attached stacking lugs that are also bent to form from sheet metal blanks; Fig. 9 showing the completed form of one of these lugs as it is applied to the corner of the crate. Briefly describing its structure, 26^a constitutes the upstanding portion or body of the lug formed by the folding of the sheet metal blank substantially mid-length thereof in such a way as to provide a hollow generally rectangular structure with substantially flat outer sides 27 at a right angle to each other, and a concave inner side 28. As shown in Fig. 1, the body 26^a of each lug is disposed inwardly of and above the upper edge of the corner portion of the crate so as to fit within a corner of the shoe frame of a superposed crate. Projecting from the lower edges of the outer sides or walls 27 of the lug are a pair of horizontal flanges or wing plates 29 that are adapted to lie flat upon the upper surface of the corner piece 14, and are provided with countersunk holes 30 registering and interfitting with countersunk holes 19 of the corner piece, in the manner clearly shown in Fig. 3. Through the holes 30 and the holes 19 and 20 of the corner piece are driven obliquely fastening nails 31. Depending from the inner wall 28 of the lug are a pair of substantially S-shaped limbs 32 (Fig. 9). When the stacking lug is attached to the corner piece 14 by the nails 31 as described, the lower hook shaped free ends 32' of the limbs 32, which are preferably sharpened to an edge, lie just above the lower limb 18 of the corner piece. Thereupon, by the use of a hammer or a suitable swaging tool, outward pressure is applied to the lower curved portions of the limbs 32 whereby their lower ends 32' are forced into the walls 10 and 11 of the box, and are securely anchored therein in the manner clearly shown in Fig. 4. This construction affords a very strong anchorage of the lugs to the inner walls of the crate body, making it practically impossible to dislodge them by outward lateral thrusts, while the fastening

nails 31 securely anchor the lugs against dislodgment from inward lateral thrusts.

From the foregoing it will be apparent that the walls of the crate are not only securely and rigidly united and bonded together at the corners by the metal angle pieces 14, but that they are effectively protected against bruising and breaking from rough handling. By extending the lips 23 upwardly against the inner sides of the bottom frame members 12 and 13, the latter are transversely clamped in such a manner as to prevent liability of splitting by the nails 21; while the lips 23 overlapping the inner sides of the upper portions of the walls 10 and 11 likewise serve to prevent splitting of said walls by the nails 31. Economy of manufacture results from making the corner pieces identical in structure and interchangeable between the upper and lower corners, while the provision of the internal lips or flanges 23 and 24 pressed snugly against the inner surfaces of the walls effectively locks the corner pieces in place even though the fastening nails should work loose or fall out. The described structure of stacking devices provides very strong and rigid stacking lugs economically manufactured from sheet metal stock, and the described means of attaching same to both the upper edges and the internal walls of the crate secures said lugs in place with a high degree of rigidity and tenacity.

In Figs. 10 to 15 inclusive I illustrate a construction dispensing with the corner angle piece reinforcement 16, and employing the stacking lugs only. The structure of the stacking lug is substantially like that previously described, but the inner depending limbs 32^a are formed substantially straight through their lower portions and are formed with rectangularly extending feet 33 that enter kerfs 34 formed in the inner surfaces of the walls of the crate adjacent to the corner, said feet having nail holes 35. Nails 36 and 37 are driven obliquely through the holes 30 in the upper flanges 29 and the holes 35 in the feet 33. It will be observed that the nail 36 is driven substantially parallel with the sides of the crate wall which receives said nail, while the nail 37 is preferably and as shown driven obliquely widthwise of the wall from near the outer surface to near the inner surface thereof. The meeting ends of the walls are united by horizontally driven nails 38 which, as clearly shown in Fig. 12, are also driven obliquely, the upper nail 38 preferably passing the nail 37 on the inner side of the latter. This construction produces a strong corner joint, and while of course the corners are not as thoroughly protected against abrasion and wear as the joint employing the angle piece 16, the construction is manifestly much cheaper and the depending limbs of the stacking lugs are

more efficiently anchored in the walls of the crate by reason of the positive holding effect of the nails driven therethrough.

While I have herein shown and described a practical and preferred embodiment of the invention which has been found in service to satisfactorily effectuate the stated purposes and objects thereof, it is manifest that minor changes in the structural details may be resorted to without departing from the principle of the invention or sacrificing any of the advantages thereof. Hence I reserve all such variations and modifications as fall within the spirit and purview of the appended claims.

I claim—

1. The combination with a rectangular crate having a shoe frame attached to the lower edges of its side and end walls, of substantially rectangular metal channel members applied to the corners of said shoe frame and disposed with their web portions overlying the outer sides of the corner portions of said frame and their flanges disposed transversely of and embracing said corner portions and projecting inwardly of the latter, the projecting portion of the lower flange being bent upwardly to lie flat against the lower corner portion of the inner side of the shoe frame and the projecting portion of the upper flange being bent upwardly to lie flat against the lower corner portion of the inner side of the superposed walls of the crate.

2. The combination with a rectangular crate having the corner portions of its upper edge countersunk and formed with transverse kerfs below and parallel with said counter-sunk portions, of substantially rectangular metal channel members applied to the said upper corners and disposed with their web portions overlying the outer sides of said corner portions and their flanges lying in said countersunk portions and kerfs, respectively, and projecting inwardly of said corner portions, the projecting portions of said flanges being bent downwardly to lie flat against the inner sides of the walls below said countersunk portions and kerfs, respectively.

3. The combination with a rectangular crate having the corner portions of its upper edge countersunk and formed with transverse kerfs below and parallel with said countersunk portions, of substantially rectangular metal channel members applied to the said upper corners and disposed with their web portions overlying the outer sides of said corner portions and their flanges lying in said countersunk portions and kerfs, respectively, and projecting inwardly of said corner portions, the projecting portions of said flanges being bent downwardly to lie flat against the inner sides of the walls below said countersunk portions and kerfs,

respectively, and fastening nails driven through said flanges and the wall portions between and below the latter.

4. The combination with a rectangular crate, of stacking lugs applied to the upper corners of said crate, said lugs each having a laterally projecting flange resting upon and secured to the upper edge of the crate and a depending limb formed with a hook 10 at its lower end anchored in the inner wall of the crate.

5. The combination with a rectangular crate, of stocking lugs applied to the upper corners of said crate, each of said lugs comprising an upstanding member of sheet metal folded upon itself, a laterally projecting flange continuous with the lower end of one of said folds resting upon and secured to the upper edge of the crate, and a depending 20 limb continuous with the other fold secured to the inner wall of the crate.

6. The combination with a rectangular crate having the corner portions of its upper

edge countersunk and formed with transverse kerfs below and parallel with said 25 countersunk portions, of substantially rectangular metal channel members applied to the said upper corners and disposed with their web portions overlying the outer sides of said corner portions and their upper and lower flanges lying in said countersunk portions and kerfs, respectively, said upper flanges having countersunk holes, stacking lugs having laterally projecting flanges formed with countersunk holes registering 35 with the countersunk holes of the upper flanges of said channel members and depending limbs formed with hook-shaped lower ends driven into the walls of the crate just above the lower flanges of said channel members, and fastening nails driven through the registering holes of said stacking lug and channel member flanges into the walls of the crate.

ARTHUR A. BERNDT.
